[57] CLAIM

The ornamental design for an adapter clamp body for
microphones or the like, as shown and described.

DESCRIPTION

FIG. 1 is a perspective view of an adapter clamp body for
microphone or the like showing my new design, the
screws shown in broken lines for illustrative purposes
only;

FIG. 2 is an enlarged elevational view of the left side
thereof;

FIG. 3 is an enlarged top plan view thereof;

FIG. 4 is an enlarged rear elevational view thereof;

FIG. 5 is an enlarged right side elevational view
thereof; and

FIG. 6 is an enlarged bottom plan view thereof.

FIG. 1
